ATTORNEY.

UNITED STATES PATENT OFFICE

2,580,998

CAN OPENER

Robert D. Colgrove, Los Angeles, Calif.

Application November 6, 1948, Serial No. 58,699

4 Claims. (Cl. 30—22)

1

My invention relates to a can opener. One of the principal objects of this invention is to provide a can opener which is primarily adapted for puncturing a can; to provide openings for pouring the contents from the can; and also for admitting air thereto to facilitate the pouring of the contents therefrom, and to provide an opener of this class which is so designed that it may also be used for cutting the lid or head from a can.

Another important object of this invention is to provide a can opener of this class having a fulcrum or pivot at one end and a can puncturing or cutting means spaced rearwardly from such end so as to provide the maximum leverage for puncturing or cutting the can.

An important object also of this invention is to provide a can opener of this class which may be formed from a simple stamping, and further one which may be formed in a single stroke of the stamping.

A further object is to provide a device of the character referred to in which the fulcrum or pivot is the pointed end of a hook adapted to be hooked under the rim or seam of the can lid; so as to adapt the device for use with cans in which the peripheral portion of the lid is merely folded over the cylindrical side of the can to provide an annular shoulder of a width equal to the thickness of the metal of the can.

A still further object is to provide a device in which the can-piercing and punching means is so constructed and arranged that it acts to fold the tab, formed by the punching operation inwardly toward the center of the lid.

With these and other objects in view, as will appear hereinafter, I have devised a can opener having certain novel features of construction, combination, and arrangement of parts and portions, as will be hereinafter described in detail, and particularly set forth in the appended claims, reference being had to the accompanying drawings and to the characters of reference thereon, which form a part of this application, in which:

Fig. 1 is a perspective view of the side of my can opener in one form;

Fig. 2 is a top view thereof, showing by dotted lines a fragmentary portion of a metal can with the opener in a puncturing position thereon;

Figs. 3 and 4 are sectional views thereof, taken respectively through 3—3 and 4—4 of Fig. 1;

Figs. 5 and 6 are respectively fragmentary side and top views of the can puncturing or cutting end of my opener in a modified form of construction;

2

Figs. 7 and 8 are respectively side and top views of the can puncturing and cutting end of my opener in another modified form; and,

Fig. 9 is a cross-sectional view, taken on line 9—9 of Fig. 2.

My can opener is made of a single piece of relatively heavy sheet metal and is made relatively long, and is of right angular cross-section. The vertical flange, designated 1, extends the full length of the opener and the horizontal flange 2 extends substantially the full length thereof; the opener thus formed being referred to as a handle or handle member. The end, designated A, provides the can puncturing or opening end whereas the opposite end portion, designated B, provides the handle for the opener when manipulating the end A for puncturing or cutting a can.

The end A has a pivot 3 which is provided at the end of a hook 4, the hook being formed as the forward part of the flange 1. The hook extends downwardly from the flange 2 and the pivot 3 is formed at the pointed end of the hook. The hook 4 is bent to one side of the plane of the flange 1, and the pointed portion or pivot 3 is formed by twisting the hook in the opposite direction, as shown best in Fig. 2. Such forming of the hook provides a pivot which may be readily positioned underneath the outer portion of the annular seam or shoulder formed by the bent peripheral portion of the can lid.

My opener has a can piercing and cutting portion 5 which is formed as a part of the flange 1 and extends downwardly as a finger from the flange 2 and is also inclined forwardly. It is spaced from, and backwardly of, the pivot 3, a distance approximately the width of the portion 5, as shown in Fig. 1. The lower edge 6 of the portion 5 is inclined at a slight angle with respect to the horizontal flange 2, the edge diverging forwardly with respect to the latter flange. The apex formed between the forward side 7 of the portion 5 and the edge 6 forms an acute angle and provides a point 8 for piercing the lid or head of the can. The length of the edge 6, backwardly from the point 8, is approximately equal to the distance of the point 8 from the pivot 3.

The cross-section of the piercing and cutting portion 5 is substantially channel-shaped, as shown in Fig. 4, and the flanges 9 and 10 at the opposite edges of the portion 5 are wedge-shaped and they diverge upwardly from the edge 6, as shown in Fig. 3.

With this construction, when the pivot 3 is engaged under the annular seam of the can, the lid or head of the latter may be pierced by means of

the point 8 when pressure is applied downwardly against the handle B, or the rear end of the flange 2. With continuing downward pressure applied to the handle the piercing and cutting portion 5 is forced into the lid or head, shearing the metal of the can and providing a relatively long hole, and with continued pressure the metal towards the center of the can is cut and the tab thus formed is rolled against the under side of the lid or head, in the direction toward the center of the lid, by reason of the wedge-shaped flanges 9 and 10, as shown in Fig. 9.

When the edge 6 is bevelled, as shown best in Fig. 3, the lid or head may be cut from the can by gradually drawing the opener around the peripheral portion of the can with the pivot 3 along the under side of the seam.

It will be noted that the point of the hook for providing the pivot 3 is made sharp in order to enable it to engage very narrow can rims and thus provide a positive fulcrum about which the can opener may be pivoted.

The piercing and cutting portions in Figs. 5, 6, 7, and 8, are substantially the same as they are described above, but the pivots for the opener are slightly different.

In Figs. 5 and 6, the forward end of the handle has a downward extension 11, and the lower end of the latter is bent towards the side of the flange 1 having the wedge-shaped flanges 9 and 10 on the piercing and cutting portion 5, forming a ledge, as indicated by 12. The pivot, in this instance, is provided at the inner end of the bent portion or ledge 12, as indicated by 13.

In Figs. 7 and 8, the forward end of the vertical flange 1 of the handle or opener is bent towards one side and also backwardly towards the piercing and cutting portion 5, as indicated by 14.

As stated above, the device is of right angular cross-section substantially throughout its length. The lower or vertical flange 1 has a cutout portion 15 at its rear end forming a crown bottle cap remover. The upper or horizontal flange 2 is substantially wide at its rear end, providing a convenient rest for the palm of the hand when using the device as a can opener or puncturing means. The edge 2^a at the rear portion of the flange 2 provides also a convenient means for removing or prying upwardly the lids of glass or other jars.

I wish it to be understood that I do not desire to be limited to the exact details of construction shown and described, for obvious modifications will occur to a person skilled in the art.

I claim:

1. A can opener, comprising a handle having a pivot portion adjacent one end, said pivot portion extending downwardly and being provided with a hook at its lower end, said hook having a pivot edge directed rearwardly from said one end and offset laterally from the vertical plane of the handle, said pivot edge extending substantially parallel to the upper longitudinal side of the handle, said handle also having a downwardly projecting cutting portion disposed intermediate its ends and provided with a lower sharpened edge, the end of said sharpened edge which is disposed nearest said hook providing an acutely pointed corner adapted to pierce the metal top of a can when forced thereagainst.

2. A can opener, comprising a handle having

a pivot portion adjacent one end, said pivot portion extending downwardly and being provided with a hook at its lower end, said hook having a pivot edge directed rearwardly from said one end and offset laterally from the vertical plane of the handle, said pivot edge extending substantially parallel to the upper longitudinal side of the handle, said handle also having a downwardly projecting cutting portion disposed intermediate its ends and provided with a lower, sharpened edge, the end of said sharpened edge which is disposed nearest said hook providing an acutely pointed corner adapted to pierce the metal top of a can when forced thereagainst, said sharpened edge being disposed at a considerable distance below said pivot edge of said hook, said sharpened edge sloping upwardly from said pointed corner of said cutting portion.

3. A can opener, comprising a handle having a pivot portion adjacent one end, said pivot portion extending downwardly and being provided with a hook at its lower end, said hook having a pivot edge directed rearwardly from said one end and offset laterally from the vertical plane of the handle, said pivot edge extending substantially parallel to the upper longitudinal side of the handle, said handle also having a downwardly projecting cutting portion disposed intermediate its ends and provided with a lower, sharpened edge, the end of said sharpened edge which is disposed nearest said hook providing an acutely pointed corner adapted to pierce the metal top of a can when forced thereagainst, said cutting portion being substantially channel shape and providing laterally projecting flanges along its substantially vertical edges, said flanges being disposed at the same side of the handle as said pivot edge.

4. A can opener, comprising a handle having a pivot portion adjacent one end, said pivot portion extending downwardly and being provided with a hook at its lower end, said hook having a pivot edge directed rearwardly from said one end and offset laterally from the vertical plane of the handle, said pivot edge extending substantially parallel to the upper longitudinal side of the handle, said handle also having a downwardly projecting cutting portion disposed intermediate its ends and provided with a lower, sharpened edge, the end of said sharpened edge which is disposed nearest said hook providing an acutely pointed corner adapted to pierce the metal top of a can when forced thereagainst, said cutting portion being substantially channel shape and providing laterally projecting flanges along its substantially vertical edges, said flanges being disposed at the same side of the handle as said pivot edge, the longitudinal edges of said flanges diverging from the plane of said cutting portion in an upward direction.
